[57] ABSTRACT

A sensing device is used in the cutting of coke from a coke drum. The sensing device relays to the cutting operator information as to the size and quantity of the coke being cut. The travel of the cutting nozzle may also be controlled automatically in response to information detected by the sensing device.

COKE CUTTING WITH AID OF VIBRATION DETECTORS

BACKGROUND OF THE INVENTION

1. Field of the Invention

The present invention relates primarily to distillation apparatus classified in U.S. Patent Office Class 202.

2. Description of the Prior Art

The inventors are aware of no related prior art. The conventional method of information flow has consisted of the operator's unassisted visual and auditory input.

SUMMARY OF THE INVENTION

1. General Statement of the Invention

By installing a listening device, or vibration detector to sense the intensity of the noise or vibration created as coke drops out of a delayed coker chamber onto a transporting chute or into a train car, a cutting operator can determine the efficiency of his cutting operation. If no coke is falling onto the transporting chute, he can move the cutting head up or down until coke begins to fall. From the amplitude of noise or vibrations that are detected, he can determine whether he is making fines or whether large chunks of coke are falling. This latter situation is preferable since fines are generally not desired. The present invention is an improvement over conventional methods of coke cutting, where the operator generally has no feedback as to how well he is doing, since steam in the area prevents him from seeing what is coming out of the chamber and the high level of water pressure that is used in the cutting process makes a loud enough noise that the operator cannot normally determine audibly if he is making any progress in his cutting operations. He is also prevented from knowing the size of the coke particles which he is producing. With the aid of the present invention, the operator can cut coke from the coker drum with a greater degree of efficiency.

A discriminating device may also be used to distinguish between low amplitude pulses and high amplitude pulses sent from the sensing device to the cutting operator. High amplitude pulses indicate that large chunks of coke are falling, whereas low amplitude pulses indicate that small chunks or fines are being cut. The ratio of high amplitude pulses to low amplitude pulses may be calculated to determine the efficiency of the cutting operation and the average size of the coke being cut. When the ratio moves away from a pre-determine value (calculated to yield a specific coke particle size), the cutting nozzle is moved on a vertical plane until the desired size of cut coke is again produced.

2. Utility of the Invention

The present invention is particularly useful for increasing the efficiency of coke cutting operations from a delayed coker chamber.

DESCRIPTION OF THE DRAWINGS

FIG. 1 shows the use of the present invention in conjunction with coke cutting apparatus.

FIG. 2 is a schematic drawing showing the use of a discriminating device to activate an automatic rate of travel control mechanism.

DESCRIPTION OF THE PREFERRED EMBODIMENTS

Sensing devices: Any type of sensing device which is capable of detecting noise, vibration, or the passage of

solid objects may be used with the present invention. In particular, a geophone comprising two segments of barium titanate (obtainable from Gulton Industries, Inc. of Metuchen, New Jersey) assembled so that a positive

5 pressure (inwardly directed radial forces) acting on one segment will contribute a positive voltage between the output terminal and the ground, whereas negative pressure (outwardly directed radial forces) acting on the other segment will contribute a positive voltage is used. Hence, the output of the detector depends upon the differences in the pressures experienced by the two segments.

Loudspeaker: The signal obtained from the sensing device may be transmitted to the operator by a conventional loudspeaker.

Oscilloscope: Any conventional oscilloscope may be used.

Examples:

EXAMPLE I

Referring to FIG. 1, a geophone 19 is installed directly below a chute 15 under a coker chamber 12. This is connected to an amplifier 21 and is transmitted through a speaker 20 in the area where the operator controls the operation. By listening to the sound from the speaker, the operator is able to tell when he is cutting efficiently and when he is not. He is also able to tell the approximate size of the particles of coke 14 which he is cutting. In response to the sound from the speaker, he may raise or lower the cutting nozzle 13 by way of the descent mechanism 22. In this manner, he is able to clean the chamber in much less time than would be possible using a conventional visual observation.

EXAMPLE II

A geophone is installed directly below a chute under a coker chamber. The signal from the geophone is transmitted to an oscilloscope. By distinguishing between high amplitude pulses and low amplitude pulses, the cutting operator may raise or lower the cutting nozzle to obtain the desired size of cut coke.

EXAMPLE III

A geophone is installed directly below a chute under a coker chamber. Referring to FIG. 2, a signal from the geophone 1 is transmitted through an amplifier 2 to a plurality of oscilloscopes 3 and 4. Oscilloscope 3 responds to high amplitude pulses received from the sensing device while oscilloscope 4 responds to low amplitude pulses. An analog computer 5 is used to calculate the ratio of high amplitude pulses to low amplitude pulses. When this ratio varies from a predetermined value, an automatic rate of travel control mechanism 6 is activated to raise or lower the cutting nozzle thereby re-establishing the desired ratio.

MODIFICATIONS OF THE INVENTION

It should be understood that the invention is capable of a wide variety of modifications and variations which will be made apparent to those skilled in the art by a reading of the specification and which are to be included within the spirit of the claims appended hereto. For example, various other types of sensing equipment may be used with the present invention, as may be various other types of signal manifesting devices. The

placement of the sensing may also be varied to adapt to the coke cutting apparatus.

What is claimed is:

1. In a method to cutting coke from the drum of a delayed coker wherein the cut coke falls from the coke drum onto a surface, the improvement comprising the use of a sensing device contacting said surface to generate a signal indicative of the amount and size of the coke and controlling the rate of the coke cutting in response to said signal.

2. A method according to claim 1 wherein a signal

from said sensing device is transmitted to the cutting operator by the use of a loudspeaker.

3. A method according to claim 1 wherein the rate of ascent or descent of the coke cutting nozzle is controlled in response to the signal from said sensing device.

4. A method according to claim 1 wherein said sensing device is a vibration detector.

5. A method according to claim 1 wherein said sensing device is a sound detector.
